UNITED STATES PATENT OFFICE.

ROY S. CUNNINGHAM, OF LOS ANGELES, CALIFORNIA.

MOTOR TEMPERATURE REGULATOR AND FUEL VAPORIZER.

1,319,271.

Specification of Letters Patent.

Patented Oct. 21, 1919.

Application filed September 3, 1918. Serial No. 252,477.

To all whom it may concern:

Be it known that I, ROY S. CUNNINGHAM, a citizen of the United States, residing at Ellis Hotel, 802 East Sixth street, Los Angeles, California, have invented a new and useful Motor Temperature Regulator and Fuel Vaporizer, of which the following is a specification.

This invention relates to the art of internal combustion, and an object of the invention is to provide an improvement in such engines as are adapted for air cooled internal combustion motors, and is especially adapted to motors that are subjected to sudden changes of temperatures such as result from the ascent of air craft from the earth in warm weather to greater altitude. In aerial navigation considerable motor trouble is experienced from the temperatures of the cylinders becoming too low at great altitudes, resulting in stalling the engine or causing the engine to miss, thus interfering with the operation of the air craft and endangering the life of the aviator.

25 An object is to provide means whereby the aviator may regulate the motor temperature so as to prevent external temperatures from affecting the same, and so that the operation of the engine will be more fully under control of the aviator at all altitudes.

A further object is to provide improved means for full vaporization and to apply air of any temperature requisite to effect the perfect vaporization of different grades of liquid fuel.

40 A further object is to provide the heat radiating ends of the motor cylinder or cylinders with a hood or housing having ventilating openings to admit air to said radiating cylinder ends, and connect said housing with the carbureter of the motor, also with the exhaust in such a manner that air will be sucked around the radiating portion of the cylinder to the carbureter and into the manifold and the cylinder during the operation of the engine; and will also be sucked by the vacuum caused by the operation of the exhaust, thus to control the flow of cooled air to the radiating end of the cylinder; and I provide means whereby the amount of air sucked past the radiating end of the cylinder may be regulated.

55 The invention is adapted for regulating through the medium of the air drawn through the carbureter; through the medium of the exhaust, or by both.

An object is to provide an improvement of this character in internal combustion engines which may be constructed in the form of an attachment for any particular type of 60 motor.

The invention is applicable to various types of air cooled internal combustion motors, and will herein be shown as an internal combustion motor having its cylinders 65 formed *en bloc*.

It is understood that the invention is applicable to an internal combustion motor having only one or any other number of cylinders and that so far as this invention is 70 concerned the same is an equivalent to the motor shown herein.

Other objects, advantages and features of invention may appear from the accompanying drawing, the subjoined detail description and the appended claims.

The accompanying drawing illustrates the invention.

Figure 1, is a side elevation of the invention applied to an internal combustion engine. Parts are broken away.

Fig. 2, is a plan view analogous to Fig. 1.

Fig. 3, is a cross section on lines $\alpha\alpha$ Figs. 1 and 2.

Fig. 4, is a front end elevation.

Fig. 5, is a plan section of the exhaust operated ejector.

The engine cylinders 1, 2, 3, 4, 5, 6, are shown as constructed *en bloc*. The radiating ends of said cylinders which project above 90 the block body 7, of the motor are provided in the usual way with radiating flanges 8, of the usual construction.

The hood or housing 9, is provided with the orifices 10, for the spark plugs of the 95 motor, and is also provided at its open end with a flange 11, which is fastened by cap screws 12, to the shoulder formed by the block of the body 7, around the cylinders.

Said housing forms an air chamber about 100 said radiating ends and is provided in its end in front of the cylinders with ports 13, to admit atmospheric air to the radiating ends of the cylinders. Said housing is also provided along its sides with air ports 14, 105 for the same purpose. A pipe 15, leads from the rear portion of the housing to the carbureter 16, which supplies fuel through the manifold 17, to the intake ports of the cylinders. The pipe 15 communicates with 110 the open air through the short circuit valve 18 so that when said valve 18 is open, more

or less air from the atmosphere may flow of the carbureter immediately without passing through the hood or housing 9.

The inlet through the valve 18 is shown 5 entering the pipe 15 through a 45 angle branch 19 so that the air entering through the valve 18 to supply the carbureter must make an abrupt turn thereby mixing cold air with the hot air drawn through the 10 hood 9.

The exhaust pipe 20 opens into the suction pipe 21, and a cylinder cooling pipe 22 communicates between the housing 9 and the suction pipe 21, and is controlled by a 15 valve 23, by which it may be entirely closed. A bypass 24, however, communicates between the interior of the housing 9, and the housing exhaust pipe 21; and a thermometer 25 is arranged subject to the heat 20 of the air flowing through the bypass so that the operator may at all times note the temperature of such air, thus to take account of the temperature of the cylinder heads, so that he can regulate the same by 25 adjusting the valves 18 and 23.

In warm weather, when starting at low altitudes, fresh air valve 18 may be widely opened, and the hood exhaust valve 23 may be also widely opened, thus to, at one and 30 the same time, supply the carbureter with the unheated atmospheric air and draw from the cylinder housing and expel from the cylinder, the heated air from the hood so that the cylinders will not become over- 35 heated. As ascent is made to the colder atmosphere, the valve 18 may be more or less closed; and as occasion requires the valve 23 may be also closed. As these valves are closed, the temperature of the cylinders is 40 increased. By regulating these two valves, the aviator may maintain the desired temperature of the engine cylinders which temperature is indicated by thermometer 25.

Starting in cold weather, the valves 18

and 23 may be more nearly closed so as to 45 conserve the heat of the engine cylinders.

An advantage gained by drawing the heated air from around the engine cylinders to supply the carbureter is as follows: to wit: the heat thus applied to the carbureter facilitates carburetion. The vaporization of the fuel by hot air in the carbureter is more complete than when cold air enters the carbureter and such vaporization lowers the temperature of the heated air so that 55 the fuel charge entering the manifold will be more thoroughly vaporized, and such charge will also be more dense and more effective than is the case where the heat is applied to the manifold instead of being 60 applied to the air before it passes through the carbureter. Furthermore the heat which is drawn from the outside of the engine cylinders is returned to the inside of the engine cylinders, thus conserving energy. 65

I claim,

1. The combination with an internal combustion engine, of a housing forming an air chamber around the engine and having openings for directing fresh air against the 70 hot parts of the engine; and means whereby the air is sucked through the openings by the suction of the engine and by the action of the exhaust.

2. The combination with an internal combustion engine, of a housing forming an air chamber around the engine and having openings for directing fresh air against the 75 hot parts of the engine, means whereby the air is sucked through the openings by the 80 suction of the engine and by the action of the exhaust, and means for regulating the flow of air through the openings.

In testimony whereof, I have hereunto set my hand at Los Angeles, California, this 85 19th day of August, 1918.

ROY S. CUNNINGHAM.
